UNITED STATES PATENT OFFICE.

JASPER LIKES, OF VENICE, CALIFORNIA.

TOY.

Application filed September 12, 1927. Serial No. 218,901.

This invention has to do generally with toys, and is more particularly concerned with toys of the type characterized as a jointed figure mounted on a handle rod and adapted 5 to be put through contortive movement through manipulation by the operator.

It may be considered as among the principal objects of the invention to provide a toy of this character which is capable of easy, 10 cheap manufacture, yet one which is sufficiently sturdy to withstand somewhat abusive manipulation by a child, and one which is capable of particularly amusing movements.

An embodiment of my invention includes 15 a handle rod and a jointed figure applied to one end of the rod. One or more of the movable elements are pivotally connected to the rod in a manner to oscillate about the point of connection, a link connecting this element to 20 an operating member which is slidable along the rod. Consequently, reciprocation of the operating member causes oscillation of said movable element, the construction being such that the element is capable of oscillating completely from side to side of the rod. This 25 makes it possible for the jointed figure to turn a complete somersault and since the other jointed elements are partially uncontrolled in their movement, a very amusing effect is 30 gained.

Other novel features will be set out in connection with the following detailed specification, reference being had to the accompanying drawings in which—

35 Fig. 1 is a perspective view of my improved toy.

Figs. 2 and 3 are side elevations of the toy showing the figure moved to different positions; and

40 Fig. 4 is a section on line 4—4 of Fig. 2.

Numeral 10 designates a handle rod carrying a head 11 at one end and a hand-grip 12 at the other. An operating member in the form of a sleeve 13 is mounted on rod 10 for 45 reciprocation or play therealong between head 11 and grip 12.

A jointed figure, generally indicated at 14, is mounted for movement on head 11. While 50 the figure may be a representation of any desired character, I have here shown a representation of a man made up of body portion 15 to which legs 16 are pivotally connected at 17 and to which arms 18 are pivotally connected at 19. The opposite ends of arms 18 55 are pivotally connected at 20 to head 11.

A link 21 extends between operating mem-

ber 13 and arms 18, the point of connection 60 22 between the link and arms being at a point intermediate pivots 19 and 20, but preferably closer to pivot 20 than to pivot 19.

While the link may be of any desired character and may be applied to the arm members 18 and operating member 13 in any desired manner, I have shown a preferred construction and mode of application. Thus, link 21 65 is made in the form of a yoke, the cross bar 23 thereof extending between and through arms 18, and the lower end of yoke arms 24 being bent inwardly at 25 through sockets or apertures 26 in member 13. Pivotal connections are thus made between bar 23 and arms 18 and between ends 25 and member 13, bar 23 and ends 25 being substantially axially parallel. 70

For purposes of easy and effective connection, the yoke may be made of somewhat springy wire, ends 25 then being sprung into sockets 25. 75

Arms 18 are thus taken between the legs 24 of link 21, and body portion 15 and head portion 15^a which may be integral with said body portion, may swing between the arms 18 without interference from yoke 21. It will be seen that arm members 18 are mounted for oscillation from side to side of rod 10, and that with grip 12 held in one hand of the operator and member 13 grasped between the thumb and forefinger of that hand, the operating member may be reciprocated to cause such oscillation of member 18 through the 90 movement of link 21. In Fig. 2 members 15 and 16 are shown as being swung by centrifugal force about their pivotal connections by reason of arms 18 having been moved suddenly upward from their position in Fig. 95 1. The body and leg members may be thus

swung to positions at the other side of rod 10 and if member 13 then be allowed to drop, the figure assumes the full line position of Fig. 3. The figure may thus be caused to turn a complete somersault, that is, be swung completely about pivots 20 on head 11 from side to side of rod 10, as indicated in full and dotted lines in Fig. 2. In either of these positions, it will be seen that the figure may be brought to rest with the several elements extending substantially parallel to the rod and at either side thereof. Since the free ends of body portion 15 and legs 16 are not positively controlled in their movement, but rather depend for their movement upon the speed and manner in which operating mem- 105 110

ber 13 is reciprocated, it will be seen that the figure may be caused to assume very amusing positions. Of course, it is not necessary to cause the figure to somersault in order to gain an amusing effect, since the movement of the figure may be confined to one side of the rod. Skill may be exercised in attempting to manipulate the toy so the figure, during successive operations, is brought into a predetermined position.

It will be readily apparent that this toy is of a simple, sturdy nature and yet one which is capable of giving very amusing effects.

It will be understood the drawings and description are to be considered merely as illustrative of and not restrictive on the broader claims appended hereto, for various changes in design, structure and arrangement may be made without departing from the spirit and scope of said claims.

I claim:

1. In a toy the combination of a handle rod, a figure embodying a plurality of pivotally connected members, one of said members being pivotally connected to the rod near one of its ends whereby said one member is adapted to oscillate about its point of connection with the rod, an operating member mounted on the rod for reciprocation longitudinally therealong, and a link connection between said operating member and said one member whereby reciprocation of the operating member oscillates said one member.

2. In a toy the combination of a handle rod, a figure embodying a plurality of pivotally connected members, a pair of said mem-

bers being pivotally connected to the rod, one at each side thereof, near one of its ends whereby said members are adapted to oscillate about their points of connection with the rod and thereby carry the figure completely from side to side of the rod, an operating member mounted on the rod for reciprocation longitudinally therealong, and a common link connection between said operating member and said pair of members whereby reciprocation of the operating member oscillates said pair of members, said connection embodying a yoke whose cross bar extends between and is applied to said pair of members and whose legs extend into pivotal connection with the operating member, said yoke being shaped and positioned to clear the rod throughout movement of the operating member.

3. In a toy the combination of a handle rod, a figure embodying a plurality of pivotally connected members, one of said members being pivotally connected to the rod near one of its ends whereby said one member is adapted to oscillate about its point of connection with the rod, an operating member mounted on the rod for reciprocation longitudinally therealong, and a link connection between said operating member and said one member between its points of pivotal connection with the rod and another member of the figure whereby reciprocation of the operating member oscillates said one member.

In witness that I claim the foregoing I have hereunto subscribed my name this 27th day of August, 1927.

JASPER LIKES.
